UNITED STATES PATENT OFFICE

CHARLES H. DASENBROOK, OF ROCKFORD, ILLINOIS, ASSIGNOR TO THAYER ACTION COMPANY, OF ROCKFORD, ILLINOIS, A CORPORATION OF ILLINOIS

PIANO ACTION

Application filed October 26, 1931. Serial No. 570,995.

This invention relates in general to the improvements in grand piano actions and more particularly to a so called simplified action in which the functions of the conventional repetition lever and associated parts are performed by a metallic spring.

The general object of the invention is to provide a novel repetition spring in a piano action of the above character whereby to 10 duplicate the key touch, the rugged construction and the reliability of operation of repetition mechanisms heretofore employed while at the same time greatly simplifying the construction of the action and reducing the cost 15 of manufacture accordingly.

More particularly, the invention resides in the novel construction of the repetition spring, in the new and improved manner of mounting the same, and in the novel construction of the different spring stops.

Other objects and advantages of the invention will become apparent from the following detailed description taken in conjunction with the accompanying drawings, in which

25 Figure 1 is a fragmentary side elevational view of a grand piano action embodying the features of the present invention, the parts being in the positions which they assume just prior to withdrawal of the jack while the 30 key is being depressed.

Fig. 2 is a perspective view of a portion of the mechanism shown in Fig. 1.

Fig. 3 is a view similar to Fig. 1 showing a modified form of the invention with the 35 parts in normal position of rest.

Fig. 4 is a view similar to Fig. 3 showing different positions of the parts.

Fig. 5 is a perspective view of the modified form of repetition spring.

40 In the exemplary form shown in the drawings, the numeral 6 indicates the conventional form of key lever carrying the back-check 7 and the capstan screw 8 which latter engages the whip 9 and throws the same upwardly upon depression of the key. Herein the whip is pivoted at 10 upon an arm 11 depending from a rail 12 which carries the rebound cushion. The butt 14 of the hammer is pivoted at 15 on the forwardly projecting flange 16 of a rail 17 and carries a

leather surfaced knuckle 18 adapted to be engaged by the upper end of the jack 19.

The jack transmits the motion of the whip to the hammer and is pivoted on the rear end of the whip with its arm 20 adapted to engage a regulating button 21 by which the jack is withdrawn from engagement with the knuckle 18 as the hammer approaches the string 22. A spring 23 acting in compression between a shoulder on the whip and the lower end of the jack, tends to move the latter in under the knuckle, this movement being limited by engagement of an adjustable and forwardly projecting button 24 on the jack with a vertical post 25.

The present invention contemplates a novel repetition spring indicated generally by the numeral 26 which is simple and inexpensive to construct and assemble in the action, which requires no mechanical adjusting 70 means, which is suited for use with several differently weighted hammers, which operates at maximum mechanical advantage in sustaining the weight of the hammer during recovery of the jack, which utilizes to advantage the upward movement of the whip in increasing the spring effect thereby permitting the use of a relatively light spring construction. To this end a spring is employed which has an elongated substantially straight 75 portion 27 extending in a direction generally parallel to a line between the axes 10 and 15 and a reversely bent portion 28 which enables the spring to be anchored near the end of the whip remote from the pivot thereof.

80 Preferably, the spring is of the hair-pin type being composed of a single length of resilient wire bent at its center so that the portions 27 and 28 are each composed of two 85 parallel parts spaced apart to receive the upper ends of the jack 19 and the post 25 between them. The upper or closed end portion 27 is bent downward slightly at its free end and adapted to engage a cushioned button 29 the stem of which is threaded into the butt flange 16 beyond the axis 15. In this way the button 29 acts as a stop for limiting the backward movement of the jack 19 and the button is located close to the knuckle 18. 90 95 100

thereby enabling proper control of the spring pressure to be obtained.

The post 25 is adapted to provide anchorage for the spring 26 at a point near the movable end of the whip and for this purpose is made of wood with a heavy base 31 (Fig. 1) having parallel sides. In this preferred form of spring, the lengths of wire forming the open end portion 28 are substantially straight and disposed in horizontal grooves 32 formed in the opposite sides of the post. The ends of the wire are bent toward each other and project into the post at one end of the groove thereby effectually anchoring such ends. At the opposite ends of the groove, the wires are firmly anchored by tacks 33 driven into the post with their heads overlying the wires. In this way the unsupported portions of the wires are firmly held against lateral as well as vertical movement and this combined with the double wire construction gives a substantial degree of lateral rigidity to the spring as a whole enabling the parts of the closed end portion 27 to be spaced relatively close to the post 25 and the jack 19 and yet maintained at all times out of rubbing contact therewith.

It will be apparent that the entire length of spring between the point of contact with the knuckle 18 and the point of anchorage in the post 25 is rendered effective with the mounting above described. Thus, the spring possesses a high degree of flexibility and is of substantially uniform strength regardless of ordinary variations in construction and mounting during manufacture. For this reason, no provision for adjustment is required and springs of the same size wire may be used for several differently weighted hammers and only a few different sizes of wire are required for all of the hammers in the action. By anchoring the spring at a point remote from the whip pivot 10, that is, adjacent the jack 19, it will be observed that full advantage is taken of the upward movement of the whip in bending the spring downwardly and thereby increasing the spring effect at the time when the spring comes into play in sustaining the weight of the hammer during recovery of the jack. The spring may therefore be made of minimum weight and high flexibility thereby making for greater uniformity in the construction of the springs.

Another way of anchoring the spring in the base of the post 25 is illustrated in Figs. 3 and 4. In this instance the ends 34 of the wire forming the spring are bent downwardly into substantially right angular relation with respect to the portions 28 and secured to the post in the same manner as in the form first described which latter is preferred because of the greater lateral rigidity obtained.

The post 25 is also utilized as a means for preventing application of the spring effect

to the hammer except during recovery of the jack. For this purpose the opposite sides of the post and the edge facing the jack 19 are hollowed out to form an upwardly inclined shoulder 35 which is padded with a piece of felt 36 and is of sufficient length of overlie the legs 27 of the spring and engage the same as shown in Fig. 2. Application of spring pressure to the hammer when the parts are in idle position is thereby prevented. With the shoulder thus located, the cost of attaching the pad 36 is reduced to a minimum inasmuch as it may be applied in strip form to a plurality of posts disposed side by side. Preferably the shoulder 35 is formed on the post directly opposite from the jack in order to form an obtuse angle with the side of the post with which it intersects thereby further facilitating attachment of the pad 36.

Assuming the parts to be in idle position (Fig. 3), the action operates as follows. When the key is depressed, the whip is thrown upwardly and its motion transmitted to the hammer through the jack. The latter is withdrawn from beneath the butt knuckle 18 as the arm 20 engages the stop 21 and the momentum of the hammer carries the latter upwardly against the string 22. If the blow is a sharp one and the key is held depressed thereafter, the back-check 7 comes into play as shown in full lines in Fig. 4 and the spring 26 is moved away from the shoulder 36 and the stop 29 thereby exerting its force on the hammer. In a similar way, as shown in dotted outline in Fig. 4, the spring 26 is out of contact with the shoulder 36 and engaging the butt knuckle following a light blow.

Now as the key is released under either of the conditions just mentioned and the back-check moves out of holding relation with respect to the hammer, the entire weight of the hammer is transferred to the spring 26 which is of sufficient strength under these conditions to support the hammer in a position such that the upper end of the jack may enter beneath the knuckle 18 without raising the latter to any appreciable degree. In this way the jack recovers quickly, that is, moves back under the knuckle thereby making possible a quick repetition of the blow. Inasmuch as the stop 29 is positioned to limit the movement of the hammer by the spring to a point where the jack just engages the knuckle in recovering, the operator senses the recovery of the jack the same as in conventional piano actions using repetition levers. In this way the key touch of present day actions is closely simulated and all of the functions of the conventional repetition lever and associated parts are performed by the spring 26 which can be manufactured and assembled in the action at a substantially reduced cost.

I claim as my invention:

1. In a piano action, the combination of a pivotally mounted hammer having a butt

knuckle, a pivotally mounted whip adapted to be actuated by depression of a key, a jack pivoted on the free end of said whip and adapted to engage at its free end with 5 said knuckle, a post rigid with and upstanding from said whip adjacent the jack pivot, and an elongated repetition spring bent intermediate its ends to form an acute angle between its end portions, one of said portions 10 extending in a direction generally parallel to said whip and anchored in said post, the other end portion of said spring extending substantially parallel to a line through the axes of said whip and hammer with its 15 free end adapted to engage said knuckle whereby to sustain the weight of the latter during recovery of said jack.

2. In a piano action, the combination of a pivotally mounted hammer having a butt 20 knuckle, a pivotally mounted whip adapted to be actuated by depression of a key, a jack pivoted on the free end of said whip and adapted to engage at its free end with said knuckle, a post rigid with and upstanding 25 from said whip adjacent the jack pivot, an elongated spring of the hair-pin type bent intermediate its ends to form an acute angle between its open and closed end portions, the ends of said open portion lying on opposite 30 sides of said post and rigidly anchored therein, the wires forming said closed end portion being disposed on opposite sides of said post and said jack and adapted to engage said knuckle adjacent the closed end of the 35 spring.

3. In a piano action, the combination of a pivotally mounted hammer having a butt knuckle, a pivotally mounted whip adapted to be actuated by depression of a key, a jack 40 pivoted on the free end of said whip and adapted to engage at its free end with said knuckle, a post rigid with and upstanding from said whip adjacent the jack pivot, an elongated piece of resilient wire bent at its 45 center to form a spring of the hair-pin type bent intermediate its ends to form open and closed end portions extending at an acute angle to each other, substantial lengths of the wires forming said open portion being 50 disposed in grooves on opposite sides of said post with the ends of the wire bent toward each other and projecting into the post near one end of said grooves and tacks driven into the post adjacent the opposite end of the 55 grooves with their heads overlying the wire, the closed end portion of said spring being arranged for engagement with the under side of said knuckle.

4. In a piano action, the combination of 60 a pivotally mounted hammer having a butt knuckle, a pivotally mounted whip adapted to be actuated by depression of a key, a jack pivoted on the free end of said whip and adapted to engage at its free end with said 65 knuckle, a post rigid with and upstanding

from said whip adjacent the jack pivot, an elongated piece of wire bent at its center to form a spring of the hair-pin type having open and closed end portions with the former anchored in said post, said closed end portion being inclined upwardly and adapted for engagement with said knuckle during recovery of said jack, and shoulders formed at the upper end of said post for engaging both sides of said closed portion. 70

5. In a piano action, the combination of a pivotally mounted hammer having a butt knuckle, a pivotally mounted whip adapted to be actuated by depression of a key, a jack pivoted on the free end of said whip and adapted to engage at its free end with said knuckle, a post rigid with and upstanding from said whip adjacent the jack pivot, an elongated piece of wire bent at its center to form a spring of the hair-pin type having open and closed end portions with the ends of the wire disposed on opposite sides of said post and anchored therein to support said closed end portion, the lengths of wire forming the latter being disposed on opposite sides of said post and jack and spaced so as to be out of rubbing contact therewith but engageable with said knuckle, and cushioned shoulders formed on said post at the upper end thereof to limit upward flexing of said 85 spring. 90

6. In a piano action, the combination of a pivotally mounted hammer having a butt knuckle, a pivotally mounted whip adapted to be actuated by depression of a key, a jack pivoted on the free end of said whip and adapted to engage at its free end with said knuckle, a repetition spring of the hair-pin type having an elongated substantially straight closed end portion extending in a 100 direction generally parallel to a line through the axes of said hammer and whip and adapted to engage the under side of said knuckle, and a single post rigid with and upstanding from said whip providing an anchor for the 105 open end portion of said spring and a stop for limiting the upward movement of said closed end portion. 110

7. In a piano action, the combination of a pivotally mounted hammer having a butt 115 knuckle, a pivotally mounted whip adapted to be actuated by depression of a key, a jack pivoted on the free end of said whip and adapted to engage at its free end with said knuckle, an elongated repetition spring supported by said whip and having a vertically movable substantially straight portion adapted to engage said knuckle, a post rigid with and upstanding from said whip and having a shoulder constituting a stop for 120 limiting the upward movement of said portion and formed on the side of said post adjacent said jack, said shoulder extending across the entire width of the post and projecting beyond the opposite sides thereof, 130

and a strip of cushioning material on the surface of said shoulder.

8. In a piano action, the combination of a pivotally mounted hammer having a butt knuckle, a pivotally mounted whip adapted to be actuated by depression of a key, a jack pivoted on the free end of said whip and adapted to engage at its free end with said knuckle, an elongated repetition spring supported by said whip and having a vertically movable substantially straight portion adapted to engage said knuckle, and a post rigid with and upstanding from said whip and having an elongated shoulder extending transversely of said post with its ends projecting beyond opposite sides thereof and providing stops for engaging said portion and thereby limiting upward movement thereof, the plane of the shoulder surface forming an obtuse angle with the side of the post from which the shoulder is cut.

9. In a piano action, the combination of a pivotally mounted hammer having a butt knuckle, a pivotally mounted whip adapted to be actuated by depression of a key, a jack pivoted on the free end of said whip and adapted to engage at its free end with said knuckle, an elongated repetition spring supported by said whip and having a vertically movable substantially straight portion adapted to engage said knuckle, and a post rigid with and upstanding from said whip and having a downwardly facing shoulder formed by hollowing out said post on the side along which said spring portion extends, a second shoulder intersecting said first mentioned shoulder and formed by hollowing out a side of said post disposed transversely of said spring portion, and cushioning means secured to and extending along said second shoulder and overlapping a portion of said first mentioned shoulder.

10. In a piano action, the combination of a rail with a flange projecting therefrom, a hammer having its butt end pivoted on said flange, a key-actuated whip, a jack pivoted on said whip and adapted to engage a butt knuckle on said butt end, an elongated repetition spring supported from one of its ends by said whip and having the other end extending in a direction substantially parallel to a line through the axes of said hammer and said whip and adapted to engage said knuckle and assist in the recovery of the jack thereunder, a screw threading into said flange between the edge thereof and the axis of said hammer so as to be disposed close to said knuckle, and a button on the end of said screw providing a cushioned stop for the free end of said spring and for limiting the withdrawing movement of said jack.

11. In a piano action, the combination of a pivotally mounted hammer having a butt knuckle, a pivotally mounted whip adapted to be actuated by depression of a

key, a jack pivoted on the free end of said whip and adapted to engage at its free end with said knuckle, a post rigid with and upstanding from said whip adjacent the jack pivot, an elongated wire member bent intermediate its ends to form two substantially straight legs projecting toward said jack at an acute angle relative to each other, one extending in a generally horizontal direction and having its free end anchored in said post at a point spaced above said jack, the other of said legs extending upwardly toward said jack and engageable adjacent its free end with said knuckle, and a cushioned shoulder on said post acting on said last mentioned leg intermediate the ends thereof to limit upward flexing thereof.

In testimony whereof, I have hereunto affixed my signature.

CHARLES H. DASENBROOK.
